FIG. 2.

FIG. 3.

INVENTOR.

BY C. J. MILLER

JAMES MCGEE, JR.,
ATTORNEY.

Patented Oct. 17, 1922.

UNITED STATES PATENT OFFICE.

CHARLES J. MILLER, OF MOSELLE, MISSISSIPPI.

RAILWAY SWITCH.

Application filed June 17, 1922. Serial No. 568,946.

To all whom it may concern:

Be it known that I, CHARLES J. MILLER, a citizen of the United States, residing at Moselle, in the county of Jones and State 5 of Mississippi, have invented new and useful Improvements in Railway Switches, of which the following is a specification.

My present invention pertains to railway rolling stock, and it contemplates the 10 provision of means by which the facing points of a railway switch are held securely to the main line rails in such a manner that they will not casually open or change position in the event of breakage of the throw rod, 15 bridle, tie bars or appurtenances of the switch and switch stand.

The invention further contemplates the provision of means whereby one point will be firmly held in proper position to one 20 main line rail and the opposing point as firmly and securely held in open position with respect to its adjacent rail; said locking means being so constructed and arranged that it tends to re-enforce the facing 25 points where they are secured to the main line connections.

Other advantages and characteristic features of this invention will be fully understood from the following description and 30 claims, when the same are read in connection with the drawings, accompanying and forming part of this application, in which:

Figure 1 is a top plan view of a railway switch equipped with my novel construction.

Figure 2 is a view partly in section illustrating the switch points set and locked to the main line connections.

Figure 3 is a similar view showing the points as unlocked with the rail set for a 40 siding.

Similar numerals of reference designate corresponding parts in all of the views of the drawings.

I deem it expedient to state, before entering into a detailed description of this invention, that in order to maintain operation of railway trains at the maximum of safety, it is highly important that facing points of a switch at their connection forming the 45 main line rails, should at all times be so secured that they would form as nearly as possible a continuous rail after the manner of the ordinary well known rail joints, and so arranged that the breakage of the rods 50 and other appurtenances would not conflict with moving trains due to the creeping or

opening of the switch points, and it is to produce a device for such purpose that I provide my novel construction comprising in connection with the well known rails 2, 60 ties 1, switch points 3, tie bar 4, throw bar 5 and a switch stand 6, the elements herein-after referred to in detail.

Under ordinary circumstances the throw rod 5 and one of the tie bars 4 are secured 65 to each other and depend upon the adjustment of the switch stand lever to keep the points 3 close up to the rail connections, but in such case should the elements fail due to breakage, the points 3 would move from 70 their proper positions to produce a great element of danger to the moving train.

As will be observed from the drawings, I produce two separate and distinct arrangements for the main line connection and the 75 side main line connection, but these elements are actuatable synchronously upon movement of the switch stand lever.

The main line connection element comprises the locking device 7 consisting of a 80 plate constructed and arranged to fit the base of the point 3 and slidable with said point on the plate 8. An arm 9 assists in locking the point 3 and this arm 9 is fulcrumed on the locking device 7 at 10 and a 85 link or lever 11 is secured to the arm 9 and connects with the throw rod 5, actuatable by the lever 6 of the switch stand.

As will be manifest the throw rod 5 is connected to the switch stand lever 6, lever 90 11 and tie bar 4 and has an enlarged end portion 12 which moves on the hanger frame 13, and said portion 12 is so adjusted that it will lift the open lock arm 14, when the throw arm is actuated in one direction. 95

The hanger frame 13 is secured to the ties 1, at the points 15, 15 and supports the open lock arm 14, which arm 14 is fulcrumed at 17 on the hanger frame 13 and actuatable with the locking device 7 and its 100 appurtenances as before stated, upon actuation of the throw rod 5.

In the practical use of the invention, it is assumed that the switch is locked and securely held to the main line rail as illustrated by Figure 1, but when required to use the siding, the switch stand lever 6 is thrown and it immediately actuates the throw rod 5 to open the locking device 7 by the lever 11 and also the locking arm 14 110 by the enlarged end 12; at said point the rod 5 having used up the slack of the pocket

18, makes contact with a projection 19 on the rod 4, and pushes the switch points 3 over to opposite rail making connection as in the present usage of side tracks.

- 5 To return the switch points 3 back to the main line connection, the switch stand lever 6 is reversed actuating the rod 5 by lever 11 to move the locking device 7 and device 14 to function at the same time. At 10 this point, the switch stand lever 6 presses down the lever 20 locking the movable arm 9 of device 7, and after the switch stand lever 6 is locked in the usual way, breakage of the bars would have no effect on the 15 points 3 with regard to their positions and the rails, until the switch stand lever 6 was unlocked and lifted by a person having charge of the repair of the stand.

It will be seen that in order to provide 20 against slack of the movable arm 9 of the locking device 7, I provide the adjusting bolt 21.

It will be manifest that the device substantially increases the safe operation of a train 25 and is simple and efficient in construction and comprises no delicate elements such as are liable to be inoperative after a short period of usage, and the elements may be quickly and easily installed and removed 30 when occasion demands without the employment of skilled labor or special tools.

The invention is applicable to all forms 35 of railway switches and I reserve to myself the right to make such changes in the future construction and size and material of the device as may fairly fall within the scope of the appended claims.

Having described my invention, what I 40 claim and desire to secure by Letters Patent, is:

1. In means for safe guarding moving trains, the combination of railway rails,

switch points arranged adjacent the rails, tie bars securing the points together, plates arranged beneath the points, a locking member 45 movable on a plate and having a surface that bears on a point, an arm fulcrumed above said member and adapted to bear on one rail, a switch stand adjacent the rails, a throw rod actuatable by the stand and connected to the arm and tie bar and means 50 actuatable by the throw rod for locking the points to the rails.

2. In means for the purpose specified, the combination of rails, plates mounted below 55 the rails, switch points adjacent the rails, a locking member actuatable on one of the plates, tie bars actuatable from a switch stand, a throw bar actuatable from the stand, locking members adapted to be seated and unseated on movement of the throw bar and an arm movably connected to the throw bar and fulcrumed on one of the members.

3. In a device for safe guarding railways 60 at switch points, the combination of free running rails, switch points adjacent thereto, plates arranged below the points, a movable arm arranged on one of the plates, and adapted to move the points, an arm movably arranged adjacent one rail and adapted to 65 bear on the web thereof, a throw rod secured to the points and locking devices arranged adjacent the rails and adapted to 70 be thrown in locking position on movement of the rod in one direction and out of locking 75 position on movement of the rails in the opposite direction.

In testimony whereof I have hereunto set my hand in presence of two subscribing witnesses.

CHARLES J. MILLER.
